UNITED STATES PATENT OFFICE.

DARIUS PARKHURST, OF ST. LOUIS, MISSOURI, ASSIGNOR OF ONE-HALF TO
GEO. H. KNIGHT, OF SAME PLACE.

HEAD-BLOCK FOR SAW-MILLS.

SPECIFICATION forming part of Letters Patent No. 257,060, dated April 25, 1882.

Application filed January 16, 1882. (No model.)

To all whom it may concern:

Be it known that I, DARIUS PARKHURST, of the city of St. Louis, in the State of Missouri, have invented a certain new and useful Improvement in Saw-Mill Head-Blocks, of which the following is a full, clear, and exact description, reference being had to the accompanying drawings, forming part of this specification.

10 My invention relates to a head-block which can be readily attached to any carriage; and my invention consists broadly in combining the index, the ratchet, and the brake-wheels in one, as clearly set forth hereinafter, and 15 shown in the drawings, in which—

Figure 1 is a perspective view, showing the frame of the block or set-works secured to the timbers of a carriage, and showing one of the knees. Fig. 2 is a side view of part of the operating-lever and the device for keeping the pawl in any one of three positions. Fig. 3 is 20 a top view of the block, and Fig. 4 is a side elevation of the same. Fig. 5 is a side elevation of part of the wheel, showing the ratchet-teeth on the under side of the rim. Fig. 6 is a detail view, showing a portion of the wheel, the index, and a portion of the shaft. Fig. 7 is a 25 detail view of the upper end of the index, showing the rib which engages with the index-teeth. Fig. 8 is a view of the wheel and adjacent parts from the inner side.

A represents the frame, which is connected to the carriage-timbers substantially as shown in Fig. 1.

30 B is the main shaft, which has journal-bearings in suitable boxes, C C, secured to the frame. Keyed to this shaft is a bevel cog-wheel, D, engaging with a similar wheel, E, keyed to the end of the counter-shaft F, having journal- 35 bearing in boxes G G, secured to the frame.

On the shaft F is the wheel H, lever I, index J, collar K, and band-wheel L. (See Fig. 1.) The lever I and index J are loose upon the shaft, so that they do not necessarily turn with 40 it. The wheel H has spokes M and a rim, N, with a flange, M'. On the outer vertical face of the rim N are index-teeth N'. The index J is located on the outer side of the wheel, and it has a rib, o, (see Figs. 6 and 7,) for engaging 45 with the index-teeth. The index terminates in a handle for moving it, when desired,

and its lower portion is made thin, so as to act as a spring to keep the rib o in engagement with the teeth, and at the same time to allow it to be disengaged therefrom, when desired, 55 by a side strain. The collar K is between the index and the journal-box of that end of the shaft, and its office is to keep the index up close against the wheel.

Q is an arm secured to the frame A in front 60 of the wheel. It has an inclined side against which the index strikes, and it also has notches R R', which engage with the rib o of the index, as hereinafter set forth.

Secured to the frame behind the wheel is a 65 safety-cam, S, its purpose being to disengage the index from the wheel to avoid all danger of breaking the teeth should the wheel be turned backward too far—as, for instance, in rolling on a heavy log, when it strikes the knees their 70 tendency to retreat will cause the backward rotation of the shaft B, which would act in turn on the counter-shaft F and consequently on the wheel H; and it is desirable that the parts should thus give way to a heavy sudden strain 75 of this kind upon the knees, for it avoids danger of breakage of the parts. By applying the brake to the wheel the parts will be kept from moving backward too far.

The rim N outside the flange M', is made 80 smooth and forms the bearing-surface for the friction-strap brake T, connected by one end to the frame A, (see Fig. 4,) and by the other end to the inner end of the lever U, which is fulcrumed to a standard, U', secured to and 85 extending upward from the frame A. The lever is notched or serrated on its upper edge or face so as to be engaged and held to any adjustment by a pawl or dog, V, pivoted to the frame. (See Figs. 3 and 4.)

90 On the inside of the rim N are ratchet-teeth N', which may be engaged by either member of a reversible pawl, I', pivoted to the lever I, and thus the wheel can be turned by the lever I in either direction, and consequently the shafts F and B, which cause the backward or forward movement of the knees. The pawl is reversed by means of the handle N'.

To keep either member of the reversible pawl in contact with the wheel, or to keep the pawl 100 out of engagement with the wheel altogether, I employ the following device.

N^3 (see Fig. 2) is a block rigidly secured to or forming a part of the same rivet or bolt as the pawl on the other side of the handle, and having a notch in the center of its lower end.

5 Against this lower end of the block bears a V-shaped cam, N^4 , whose stem N^5 works in lugs N^6 on the lever.

N^7 is a spiral spring surrounding the stem of the cam between the lugs, which holds the cam in contact with the block. When the pawl is out of engagement with the wheel the cam rests in the notch of the block, and when either member of the pawl is in engagement with the wheel the opposite lower edge of the block bears against the inclined face of the cam, (see dotted lines, Fig. 2.)

W is a guide-bar for the lateral support of the lever. It is secured to the frame by its opposite ends, and on it is a stop, W' , which may be used to limit the forward movement of the lever.

X is a gage-bar secured to the frame, having a stop, V , with a set-screw, Z . This bar is marked off into inches and parts thereof.

25 The operation of the machine is as follows: Before rolling a log onto the carriage the pawl is thrown out of engagement with the wheel, and the index is also thrown out of engagement with the wheel by engaging it with notch R' of the arm Q , and the brake applied. Then

30 when the log strikes the knees they will be allowed to give slightly, together with the other parts, as and for the purpose set forth. The pawl is then thrown into engagement with the wheel and the parts turned forward, which

35 moves the log up to the saws; or, if the log is to be moved from the saws, the other member of the pawl is thrown into engagement with the wheel, and the parts moved backward, (the brake of course having been removed, or partially so, as desired.) Generally when

40 a log is being slabbed which does not require a careful adjustment it would be quicker to move it by means of the hand-wheel L , which is keyed to the outer end of the shaft F for that purpose. When the hand-wheel is thus used the pawl and index are thrown out of engagement with the wheel.

I will now suppose that the log has been 50 slabbed and moved up to the saws, and that it is desired to cut a one-inch board therefrom. The stop Y is first moved to the numeral 1 on the gage-bar and secured thereby by the set-screw, when the index, being in front of the stop, is brought back until it comes against the stop, when it is engaged with the teeth of the wheel. Next, the wheel is moved forward until the rib on the index engages with the notch R in the arm Q , which stops the forward movement 55 of the wheel, for it will still be engaged by the index. This will move the log toward the saws one inch, and the operation can be repeated as often as desired; and if it is desired to cut a thicker or thinner board the stop Y would be 60 accordingly adjusted on the scale-bar and the index moved up to it each time.

The scale-bar may be marked off into eighths and sixteenths of inches, if desired; but it is about as easy to count the teeth on the wheel for anything less than a quarter of an inch, as each tooth represents a sixteenth-of-an-inch movement of the knees. As a rather inferior modification of the gage-bar the periphery of the wheel might be graduated or the guide W graduated and the distance measured by the operating-lever. I prefer to make the ratchet-teeth the proper distance apart for each one to represent a one-sixteenth-of-an-inch movement of the knees, so that in the drawing back the lever each click of 80 the pawl will represent such movement, and thus the distance may be measured by the ear.

The brake is not only useful when the log is being rolled on, as described, but it is also useful at any other time to prevent a return 85 movement of the knees under pressure of the log. Its character allows its force to be varied at will, as can be plainly seen.

Having thus described my invention, the following is what I claim as new therein and desire to secure by Letters Patent:

1. In a head-block for saw-mills, the combined index, ratchet, and brake-wheel, in combination with suitable lever, index, and brake, as set forth.

2. In a head-block for saw-mills, the wheel H , with rim N , ratchet-teeth N' , and index-teeth N'' , in combination with arm J and lever I , carrying reversible pawl, substantially as and for the purpose set forth.

3. In a head-block for saw-mills, the index, ratchet, and brake-wheel combined in one, in combination with a lever, I , having reversible pawl I' , an index, J , and a brake, T , to receive the rebound, all substantially as specified.

4. The combination of wheel H , lever I , provided with pawl I' , brake T , index J , and arm Q , with notches R R' , substantially as specified.

5. In a head-block for saw-mills, the cam S , in combination with the wheel H and index J , secured to the frame A for the purpose set forth.

6. In a head-block for saw-mills, the wheel H , lever I , provided with a pawl, I' , arm Q , and index J , the latter being made thin so as to act as a spring, and having a rib, o , for engaging with the teeth of the wheel and with notches of the arm Q , all substantially as and for the purpose set forth.

7. In a head-block for saw-mills, the combination of wheel H , lever I in rear, reversible pawl I' , index J in front, shaft T , arm Q , cam S , brake T beneath the wheel, lever U , pawl V , scale-bar X , provided with stop Y , all supported by the frame A , and the shaft F , engaging with the main shaft B , all substantially as and for the purpose set forth.

DARIUS PARKHURST.
